UNITED STATES PATENT OFFICE.

CHANCY C. ANDREWS, OF NOTTAWA, MICHIGAN.

WAGON-TONGUE LOCK.

SPECIFICATION forming part of Letters Patent No. 396,189, dated January 15, 1889.

Application filed June 30, 1888. Serial No. 278,702. (No model.)

To all whom it may concern:

Be it known that I, CHANCY C. ANDREWS, a citizen of the United States, residing at Nottawa, in the county of St. Joseph and State of Michigan, have invented certain new and useful Improvements in Wagon-Locks; and I do hereby declare the following to be a full, clear, and exact description of the invention, such as will enable others skilled in the art to which it appertains to make and use the same.

My invention relates to a device for preventing lateral vibrations of the wagon-tongue when the front wheels come in contact with an obstacle in the roadway, so that the horses will not become injured from being struck with the tongue.

The object of my invention is to provide mechanism which will be much more simple, cheap, and durable than that hitherto in use.

With these ends in view my invention consists in the peculiar features and combination of parts more fully described hereinafter, and pointed out in the claims.

Referring to the accompanying drawings, Figure 1 represents a plan of my complete device; Fig. 2, a front perspective view, showing the tongue slightly turned and in the act of unlocking the front axle.

The tongue B is pivoted at a to the front cross-brace, b, of the hounds D D', and its short arm B' plays laterally between the blocks d d', which blocks taper as they extend rearward to form the space e, in which said end plays. A horizontal rod, E, extends through the hounds D D', blocks d d', and short arm B' of the tongue, and this rod is provided with stops

g g' to limit the play of the tongue. These stops g g' consist of nuts which can be turned

on the thread h, so that the stops can be regulated to allow any desired amount of play for the tongue. The rear end of the tongue is provided with a projection, q, which fits in the recess r in the center of a bar, c, which is ar-

ranged to be reciprocated horizontally in the staples K upon the hounds D D'. This reciprocating bar might be passed through apertures in the hounds or placed in any suitable guides instead of the staples. Said bar c is provided with a pair of elongated apertures, l, which extend vertically through it.

b b' represent a pair of horizontal rods or

levers, which pass through and rotate in the head-blocks s and brace-bar t. The front ends, u u', of these rods b b' are bent downward and 55 confined within the apertures l in the bar c. The rear ends, m m', of the rods b b' are bent at right angles toward each other and thence inward through the locking-latches o o', pivoted to the rods b b', which latches operate in a vertical plane in the elongated opening p through the upper portion of the brace-bar t.

The usual reach, W, extends through the elongated opening X in the brace-bar t. The ends m m' pass through that part of the latches 65 which extends above the brace-bar, and the bar thus holds the latches in operative position. The recess r in the reciprocating bar c is formed by lugs i i', the object being to form a loose connection between the end B' of the 70 tongue and bar. In order to prevent undue wear upon the reach by the operation of the latches, the former is provided with a pair of shield-plates, y, made of any suitable metal.

It is desirable that the free ends of the pivoted locking-latches should be weighted in order to facilitate their descent into locking adjustment, and for this reason I have by preference given them an approximate wedge shape, as will be seen more clearly in Fig. 2. 75 80

The body portions of the rear ends of the rods or rock-shafts b b' pass loosely through the light ends of the latches, and their ends m m' are bent and passed loosely through the upper part of the weighted ends. By this 85 construction a greater leverage is obtained than if the body portions of the rock-shafts were rigidly connected to the light ends of the latches.

The way in which I prefer to construct my 90 invention having been set forth, I will now proceed to describe its operation.

When one of the wheels G comes in contact with an obstacle in the roadway, its axle is prevented from turning by the latches o o', which 95 normally hold the hounds D D' and cross-braces b t, forming the fifth-wheel Z, in such a position that the axle A will be substantially at right angles to the reach W, as shown in Fig. 1. As shown more clearly in Fig. 2, when 100 lateral power is exerted upon tongue B the short arm B' moves in the opposite direction and slides the rod c, which carries with it the crank or end u, located in aperture C, and ro-

tates the rock-shaft *b*, thereby elevating its opposite end, *m*, which lifts latch *o* and allows the fifth-wheel to turn upon its king-bolt *z*. When pressure is brought to bear on the tongue in an opposite direction, the reverse operation takes place, the rod *b* just described remaining still, while its companion, *b'*, raises the latch *o'*. Thus the rotative rods alternately lift the latches *o o'* to allow the front axle or fifth-wheel to turn in the direction given by the movement of the tongue. Thus it will be observed that when lateral power is exerted upon the tongue the latches are raised and the fifth-wheel rotates freely; but when the wheel is locked in its normal position it cannot be turned by the wagon-wheels coming in contact with obstacles in the roadway. By this construction the cams, which have hitherto been considered necessary, are dispensed with and a great amount of sliding friction is overcome, thus rendering the parts more durable.

Having thus described my invention, what I claim as new, and desire to secure by Letters Patent, is—

1. In a wagon-lock, a pivoted tongue and movable bar engaged thereby, in combination

with a rock-shaft having one end engaged by said bar and the other end provided with a locking-latch, substantially as described. 30

2. In a wagon-lock, a fifth-wheel and pivoted tongue, in combination with rock-shafts provided with locking-latches, substantially as described.

3. The combination of a fifth-wheel provided with a pivoted tongue, a horizontal bar passing through the tongue and provided with stops upon opposite sides thereof, a reciprocating bar, a pair of rock-shafts engaged by said bar, and locking-latches operated by said shafts, all arranged and adapted to operate substantially as described. 35 40

4. In combination with the fifth-wheel and tongue, a pair of rock-shafts having locking-latches pivoted thereon, and having their 45 heavier free ends also pivotally connected to the bent ends of the shafts, substantially as described.

In testimony whereof I affix my signature in presence of two witnesses.

CHANCY C. ANDREWS.
